All Office Actions; U.S. Appl. No. 29/679,544, filed Feb. 7, 2019.
 (Continued)*Primary Examiner* — Jennifer Rivard*(74) Attorney, Agent, or Firm* — Kevin C. Johnson(57) **CLAIM**

The ornamental design for an electric dry shaver head, as shown and described.

DESCRIPTION

FIG. 1 is a perspective view of an electric dry shaver head;
 FIG. 2 is a front view thereof;
 FIG. 3 is a right side view thereof;
 FIG. 4 is a rear view thereof;
 FIG. 5 is a left side view thereof;
 FIG. 6 is a top plan view thereof; and,
 FIG. 7 is a bottom view thereof.
